(57) **CLAIM**

The ornamental design for a light mount, as shown and described.

DESCRIPTION

FIG. 1 is a perspective view of a light mount showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the light mount where the light mount is in a configuration of use; and,

FIG. 10 is an enlarged view of portion 10 shown in FIG. 1. The dash-dash broken lines in the drawings depict portions of the light mount that form no part of the claimed design. The dot-dash broken lines represent boundaries of the enlarged portion and form no part of the claimed design. The broken lines in FIG. 9 showing light mount depict environment and form no part of the claimed design.

1 Claim, 10 Drawing Sheets
